UNITED STATES PATENT OFFICE.

STEPHEN P. BROOKS, OF SOMERVILLE, MASSACHUSETTS.

PIANO-FORTE ACTION.

SPECIFICATION forming part of Letters Patent No. 439,633, dated November 4, 1890.

Application filed February 20, 1888. Serial No. 264,696. (No model.)

To all whom it may concern:

Be it known that I, STEPHEN P. BROOKS, a citizen of the United States, residing at Somerville, in the county of Middlesex and State 5 of Massachusetts, have invented a new and useful Improvement in Piano-Forte Actions, of which the following is a specification.

My invention consists, first, in the peculiar construction and arrangement of an independent back-catch in which the fly when the key is depressed passes into a slot in the rocker upon the key-lever and holds the hammer at any desired distance from the string, and causes it to repeat against the string at 15 the slightest motion of the key-lever; second, the hammer is held from repeating against the string by a lever extending from the fly; third, the lever extending from the fly causes it to return upon the butt instead of a spring 20 when the key returns to its normal position; fourth, the standard in the rocker in the rear of the fly extends up near the flange-joint of the fly, and the fly extending downward to the butt makes a double leverage to relieve 25 the hammer the instant it strikes the string.

To enable others skilled in the art to understand and use my invention, I will proceed to describe the manner in which I have carried it out, reference being had to the accompanying drawings, in which—

Figure 1 represents a side view of a piano-action in its normal position embodying my invention. Fig. 2 shows a similar view with the key depressed.

35 A represents the key-frame, to which the key-lever B is attached in the usual manner. Near the end of the key-lever B is attached the rocker C. The fly D is pivoted by a flanged joint d to the lever E, and the end of 40 the fly D works in a slot F in the rocker C.

G is a lever attached to the fly D, which holds the hammer in position when the key is depressed and causes the fly D to return on the butt H when the key returns.

45 I is a rail, to the top of which is secured the

block J, in which the lever E is pivoted, and to which the hammer K is attached by a stem R.

L is the hammer-rail, upon which is a cushion l, on which the hammer rests when the 50 key is in position of rest, as in Fig. 1, and as the key-lever B is depressed it brings the hammer against the string M, as required.

N is a stop-button attached to a regulating-screw O, which passes through the fly D. 55 This stop when the hammer is raised presses against the standard P upon the rocker C and causes the lower end of the fly D to pass into the slot F in the rocker C, and relieves the hammer from the string. By means of 60 this device the hammer is held near the string M, so that a rapid repetition of a note can be easily effected by a very slight motion of the key-lever B, which is not the case when the ordinary back-catch is employed. 65

What I claim as my invention, and desire to secure by Letters Patent, is—

1. The lever E and fly-lifter D, in combination with the lever G and rocker C, provided with a slot F and butt H as a back-catch to 70 hold the hammer after the blow is given, substantially as described.

2. The lever G, in combination with the fly-lifter D, for returning the latter upon the butt H without the employment of a spring, 75 substantially as described.

3. The key-lever B, rocker C, provided with slot F, butt H, and standard P, in combination with the rail I, block J, lever E, stem R, hammer K, fly-lifter D, and lever G, operating 80 substantially in the manner and for the purposes set forth.

In testimony whereof I have signed my name to this specification in the presence of two subscribing witnesses.

STEPHEN P. BROOKS.
